UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,857, dated November 1, 1887.

Application filed September 21, 1887. Serial No. 250,350. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by

10 the pattern will appear.

The design shows a basque and a round walking skirt. The skirt displays a pointed drapery at the right side depending from its upper corners, where it exhibits draping 15 plaits, the drapery revealing the skirt between the corners to quite a depth below the top, a left side drapery that forms jabot folds at its back edge and side plaits in front of the jabot folds, a straight back drapery that falls in

side plaits at the center, and a jabot drapery 20 that rests upon the left side of the back drapery. The basque exhibits close-fitting fronts that display a closing below the bust and flare to the shoulders above the latter, exposing a narrow-pointed vest, a close-fitting back that 25 exhibits underfolded plaits below the waistline of its middle three seams, a standing collar, and coat-sleeves with pointed puffs at their tops.

What I claim as my invention, and desire to 30 secure by Letters Patent, is—

The design for a lady's costume, as shown in the engraved prints accompanying this specification.

JENNIE SHEILS.
